UNITED STATES PATENT OFFICE

147,135

DESIGN FOR A COMBINED CHILD'S VEHICLE AND PACKAGE CARRIER

Peter Moran, Cleveland, Ohio

Application February 25, 1946, Serial No. 126,902

Term of patent 14 years

(Cl. D14—3)

To all whom it may concern:

Be it known that I, Peter Moran, a citizen of the United, residing at Cleveland, in the county of Cuyahoga and State of Ohio, have invented a new, original, and ornamental Design for Combined Child's Vehicle and Package Carrier, of which the following is a specification, reference being had to the accompanying drawing, forming a part thereof, in which:

Fig. 1 is a side perspective view of a combined child's vehicle and package carrier showing my new design; and

Fig. 2 is a front view thereof.

I claim:

The ornamental design for a combined child's vehicle and package carrier, substantially as shown.

PETER MORAN.
